(57) **CLAIM**

The ornamental design for an inflatable head and neck protection device as shown and described.

DESCRIPTION

1. Inflatable head and neck protection device

1.1 : Perspective

1.2 : Front

1.3 : Back

1.4 : Left

1.5: Right

1.6: Top

1.7: Bottom

Reproduction 1.1 is a perspective view of an inflatable head and neck protection device showing our new design; reproduction 1.2 is a front elevation view thereof; reproduction 1.3 is a rear elevation view thereof; reproduction 1.4 is a left side elevation view thereof; reproduction 1.5 is a right side elevation view thereof; reproduction 1.6 is a top plan view thereof; reproduction 1.7 is a bottom plan view thereof. Portions of the inflatable head and neck protection device shown in broken lines form no part of the claimed design.
